ANCHOR

Bruno R. Zepa, Chicago, Ill.

Application March 30, 1936, Serial No. 71,726

2 Claims. (Cl. 114—208)

My invention relates to anchoring devices and has among its objects and advantages the provision of an improved anchor, including means for rendering the anchoring arms inoperative for holding purposes when a pre-determined pulling force is applied to the line connected with the anchor.

In the accompanying drawing:

Fig. 1 is a plan view of the anchor showing the holding blades folded;

Fig. 2 is a sectional view along the line 2—2 of Fig. 1;

Fig. 3 is a sectional view along the line 3—3 of Fig. 2;

Fig. 4 is a sectional view along the line 4—4 of Fig. 2; and

Fig. 5 is a sectional view along the line 5—5 of Fig. 2.

In the embodiment selected to illustrate my invention, I make use of a tubular body 10 comprising sections 12. These sections include flanges 14, arranged in overlapping relation, and provided with openings for the reception of rivets 16 for firmly connecting the sections together. The opposite end of the housing 10 is closed by means of a cap 16, the flange 18 of which embraces the outer wall of the housing. A rivet 20 passes through openings 22 in the housing, and slots 24 in the flange 18 for holding the parts in assembled relation.

A plurality of holding arms 26 is pivotally connected with the housing 10. Slots 28 are provided in the housing for receiving the ends 30 of the arms 26, which ends are arranged at right angles to the major positions of the arms by bending the latter.

On the outer surface of the housing 10 I weld a plurality of straps 32, each having both ends bent to provide flanges 34. These flanges are grouped in pairs adjacent the slots 28 and are spaced for freely receiving the ends 30. Rivets 36 pass through aligned openings in the grouped flanges 34 and the ends 30 to provide pivotal mounting for the arms 26.

In Fig. 2, the full line position of the arms 26 illustrates the holding position of the arms while the dotted line position illustrates the shifted position of the arms for releasing the anchor. Within the housing 10, I mount a pistonlike member 38 which is circular in cross-section, and arranged to move freely within the housing. This member is provided with a transverse slot 40 for accommodating a rivet 42 fastened to the sections 12 for additionally connecting the sections into a unitary whole.

One end of the member 38 is arranged to bear against the ends 30 as indicated at 44. Means for holding the member 38 in the full line position of Fig. 2 comprises two arms 46, having their ends 48 arranged to engage the member in the manner illustrated in Fig. 4.

Each arm 46 comprises two spaced flanges 50, connected by crossbars 52. One of the arms 46 is offset, as at 54, to accommodate the other arm which passes therethrough. The two arms are pivotally connected by a shaft 56, which passes through a slot 58 in a releasing bar 60 and has its ends riveted to the housing 10 (see Fig. 2). Links 62 are pivotally connected with the arms 46 at 64 and with the bar 60 at 66. The bar 52 at the upper end of each arm 46 is connected with the lower bar 52 of the other arm by a tension spring 68. These springs operate to normally hold the arms 46 in the full line position of Fig. 4.

The bar 60 slides freely through the opening 70 in the housing 10. With the arms 46 in the full line position of Fig. 4, the member 38 is firmly held in the full line position of Fig. 2, at which time the arms 26 are positioned for anchor purposes. The arms 26 are latched against pivotal action. The ends 30 are recessed at 72 to provide fingers 74, which engage the inner face of the flange 18, for limiting the pivotal action of the arms. The member 38 holds the finger 74 firmly against the flange 18.

I provide the bearing 60 with an opening 76 for connection with a line. The springs 68 resist forces applied to the line attached to the bar, but when the forces exceed a predetermined value, the arms 46 will be shifted to the dotted line position of Fig. 4 for releasing the arms 26. I provide the member 38 with a bore 78 for receiving the arms. Outward movement of the bar 46 relatively to the housing 10 shifts the links 62 in such a manner as to pull the upper ends of the fingers inwardly, thus shifting the lower ends of the arms towards the center of the housing.

In the latched position of the arms 26, the rivet 42 lies adjacent one end of the slot 40, as indicated in Fig. 4. When the arms 46 are shifted to the dotted line position, any pull on the anchor will shift the arms 26 to the dotted line position of Fig. 2, at which time the member 38 is shifted to the dotted line position of Fig. 4 with the lower ends of the arms 46 lying within the bar 78.

In the dotted line position of the arms 26, the ends 30 are in abutting relation with the housing 55

10, as indicated at 80. The arms 26 are arranged to be folded against the housing 10 in the manner illustrated in Fig. 1. The flange 18 is provided with slots 82 which may be aligned with the slots 28 for freeing the fingers 74. Referring to Fig. 1, the slots 24 permit the cap 16 to be rotated about the housing 10 for aligning the slots 82 as shown. The collapsible feature permits the anchor to be folded compactly for handling and transportation purposes. The bore 78 is flared at 84 to provide a gentle curvature facilitating shifting of the arms 46 to a position within the bore.

My invention provides an ideal anchor for trolley lines employed for fishing purposes. The device may be used with equal advantage as an anchor for other purposes. The amount of pull required for releasing the anchor depends upon the tension of the springs 68.

Without further elaboration, the foregoing will so fully describe my invention that others may, by applying current knowledge, readily adapt the same for use under various conditions of service.

I claim:

1. In an anchor, a supporting body having a plurality of anchoring arms pivotally connected therewith, an arm holding member movably associated with said supporting body and arranged for holding the arms in an anchoring position,

a pair of arms pivotally connected inwardly of their ends, one end of each arm being arranged to engage said member for holding the same in fixed relation with the anchoring arms, links pivotally connected with the other ends of said arms, a spring connecting one end of each arm with the opposite end of the other arm, and means movably connected with one end of each arm and actuated when a predetermined force is applied thereto for shifting the arms to a non-holding position with respect to said member. 5 10

2. In an anchor, a tubular body having anchoring arms pivotally connected therewith, a member slidably positioned within the tubular member and cooperating with the anchoring arms 15 for holding the same in an anchoring position, said member being provided with a bore, means for holding the member in a fixed position, said means comprising a plurality of arms pivotally connected together, a linkage for moving the 20 arms to different positions, said arms being arranged to engage one end of said member for holding the same against shifting, said arms being arranged for shifting to another position for reception by said bore to permit shifting of 25 the member.
